UNITED STATES PATENT OFFICE.

HERMAN FREUND, OF BROOKLYN, AND CHARLES WEBSTER GASKELL, OF NEW YORK,
N. Y., ASSIGNORS TO INTERTYPE CORPORATION, OF BROOKLYN, NEW YORK, A COR-
PORATION OF NEW YORK.

MATRIX FOR LINE-CASTING MACHINES.

Application filed January 14, 1921. Serial No. 427,180.

To all whom it may concern:

Be it known that we, HERMAN FREUND, residing in Brooklyn, N. Y., and CHARLES WEBSTER GASKELL, residing in New York city, New York, the former a German citizen and the latter a United States citizen, have jointly invented the following described Improvements in Matrices for Line-Casting Machines.

10 The invention is an improvement in the matrices used in line-casting or linotype machines. It will be understood that such matrices are the movable elements in these machines carrying the die-cavities by means of 15 which the letters or characters are cast on the linotype slug. A font of such matrices is contained in the magazine of the machine from which they are selectively delivered and grouped in line in an assembling frame 20 or elevator by the operation of the compositor's keyboard. In this elevator they are justified and then presented to the casting mechanism after which they are transported to the distributing mechanism by 25 means of which they are automatically returned each to its respective channel in the magazine. The rear edge of each matrix carries the die cavity or cavities by which its particular type-character is cast in the 30 slug and for the convenience of the operator the same character is also stamped in the surface of the front edge of the matrix so that, as the matrices are grouped in composition, these front edge reference characters 35 form a reading line of the matter so composed which is intended to enable the operator to verify his work. In the circumstances of practical use however, such reference characters become obscured and difficult 40 to read, and mistakes in composition are likely to escape notice, besides which their use imposes considerable strain on the compositor's eyesight. The matrices are commonly chamfered or bevelled at the corners 45 of their vertical front edges in order to facilitate their movement by and through the various automatic mechanisms of the machine, and when assembled in composition the adjacent chamfered corners produce

a series of vertical grooves intervening between the reference characters and breaking up the continuity of the composed line so as to interfere with reading it. The chamfering also reduces the available area of the front edge surface of the matrix so that the character applied thereto is correspondingly small, and smaller than the die character on the opposite edge. It is common practice to fill the reference character with a pigment for the sake of contrast with the surrounding surface but this is not permanently effective, because the surrounding field surface, usually a brass surface, soon becomes dirty from use thereby destroying the contrast, or if frequently cleaned, becomes so shiny as to interfere with the legibility by reflection and glare. It has been proposed to keep the matrices clean by means of brushes incorporated in the machine and automatically operating to brush them off, but the effect of this attachment is not only to remove the dirt but also the pigment from the character. Other proposals have contemplated the coloring of the field as well as the character for contrast and giving the field a surface texture not likely to retain dirt and hence not requiring the use of the brushes, but such methods besides being expensive are open to the objection that the colored surface quickly wears off at the corners of the matrix leaving a shiny brass edge, which has the same effect as the chamfer grooves in interrupting the continuity of the reading line and confusing the eye. It is the object of the present invention to improve the display of the reference characters so that they will be more quickly and plainly legible and the least likely to become illegible as the result of wear whether colored or not, and to this end, the invention consists in the use of one or more of the features hereinafter disclosed.

In the accompanying single sheet of drawing, Fig. 1 is a perspective greatly enlarged of a matrix having a chamfered front edge and incorporating such features in their preferred form.

Fig. 2, a composed group of such matrices with spacers in position, and

Fig. 3, a cross section through the reference character of Fig. 1.

5 The rear edge of the matrix which carries the casting die-cavities is marked 1. The index or reference character 2, on the front edge is stamped, bossed, cut or otherwise formed on a field surface 3 which is visibly 10 separate and distinct from the rest of the front edge, being preferably countersunk or set back from the immediately adjacent portions 4 of said edge so that when such matrices are in composition, the assembled field 15 surfaces will form a horizontal panel on which the reading line appears as indicated in Fig. 2. This panel effect is of much assistance in directing and guiding the eye when it is desired to read the line. The 20 extent to which the field surface 3 is set back, or conversely, the extent to which the adjacent portions 4 project in front of it, is subject to variation according to the style of the matrix, and general conditions. A set 25 back of even a slight amount, provides a protection to the field surface which relieves it of wear in the repeated travel of the matrix through the machine, which might otherwise polish it and thus impair its function 30 as a proper background. In the case of a chamfered matrix, it is set back at least to the base of the chamfer (5) and preferably farther, so as to give the panel effect and also take advantage of the full thickness of 35 the matrix and thereby permit the field and character to be larger than would be possible if placed as heretofore, on the front surface between chamfers. The field surface is preferably, though not necessarily, 40 located between the top and bottom lugs of the matrix and it is also cut perpendicular to the plane of the matrix which makes its vertical corners 6 sharply right-angled, so 45 that the panel formed by the assembled matrices is unbroken by the chamfer grooves as will be plain from the drawing. The individual field surfaces thus fit so closely that the panel is not appreciably interrupted by the crevices between the matrices and moreover the said corners are sufficiently 50 protected as above mentioned so that they do not become shiny from wear. The field surface may therefore be treated in any suitable 55 manner to make a desirable contrast with the character and without the objection above noted as to colored matrices; it may be and preferably is blackened by treatment with an acid and the reference character is also filled with a light colored pigment, but the surface may also be left in the 60 natural color of the brass or metal without producing glare because of the shading effect provided by the adjacent projecting portions of the matrix and because the protected field surface does not come in polishing contact 65

with any part of the linotype machine and is not likely to become polished by the cleaning brushes when used.

It will be apparent from the foregoing that the panel effect and the protection thereof constitute the principal features of the invention and that these effects may be secured by the use of other agencies than herein specifically shown for illustrating the principle of the invention and without departing from the fundamental thought. Each matrix may be formed with more than one field surface so as to form more than one reading panel when in composition, and more than one reference character may be 70 put on a field surface, as may be preferred, these and other obvious modifications being contemplated as within the scope of the invention as set forth in the following claims. It is desirable that each field surface of a 75 panel shall be of the same height as the others with which it is used and that they shall be of the same general shade and appearance to the end of producing a panel giving the greatest aid to the reading of the 80 composed line.

We claim:—

1. A matrix for use in line casting machines having a separate surface at its front edge between its top and bottom lugs constituting a field for a reference character and adapted to form a panel for the reading line of a composed group of said matrices. 85

2. A matrix for use in line casting machines having a field surface for a reference character on its front edge, set back with relation to the immediate adjacent portion of said front edge, and adapted to form a panel for the reading line of a group of said matrices. 100

3. A matrix for use in line casting machines having at its front edge, a separate, protected field surface and a reference character applied to said surface. 105

4. A matrix for use in line casting machines having a field surface for a reference character at the front edge thereof, the field and character being contrastingly colored, and means associated with said surface for protecting the color against wear by contact 110 with the machine in which the matrix is used. 115

5. A matrix for use in line casting machines having at its front edge a separate, protected surface constituting a field for a reference character and adapted to form a panel for the reading line of a composed group of such matrices, the reference character being colored for contrast with its field surface. 120

6. A matrix for use in line casting machines having chamfered vertical corners on its front edge and a field surface for a reference character at said edge as wide as the full thickness of the matrix. 125

7. A matrix for use in line casting ma- 130

- chines having a chamfered front edge, a field surface set back from said edge as far as the base of the chamfer and a reference character applied to said set back surface.
5. 8. A matrix for use in line casting machines having a chamfered front edge, a field surface therein set back as far as the base of the chamfer and colored, and a reference character having a contrasting color applied to said field surface. ¹⁰
- In testimony whereof we have signed this specification.

HERMAN FREUND.

CHARLES WEBSTER GASKELL.
